STRETCHER BARRIER

Bernard E. Shaw, 6732 Colonville Road E.,
Clare, Mich. 48617

Filed Apr. 21, 1971, Ser. No. 136,297

Term of patent 14 years

Int. Cl. D24—02

U.S. Cl. D83—1

FIG. 1 is a perspective view of a stretcher barrier incorporating the design;

FIG. 2 is a top plan view thereof;

FIG. 3 is a bottom plan view thereof;

FIG. 4 is a front elevational view thereof, it being understood that the rear elevational view is a mirror image of the view illustrated in FIG. 4;

FIG. 5 is an end elevational view thereof, as seen along the line 5—5 of FIG. 2, it being understood that the opposite end elevational view is a mirror image of the view illustrated in FIG. 5;

FIG. 6 is a top plan view of a stretcher barrier incorporating a slightly modified design;

FIG. 7 is a bottom plan view of the modified design;

FIG. 8 is a front elevational view of the modified design;

FIG. 9 is a rear elevational view of the modified design;

FIG. 10 is an end elevational view of the modified design, as seen along the line 10—10 of FIG. 6; and

FIG. 11 is an opposite end elevational view of the modified design, as seen along the line 11—11 of FIG. 6.

I claim:

The ornamental design for a stretcher barrier, as shown and described.
